Edwin L. Smalley Inventor
By his Attorney J. W. Walker

UNITED STATES PATENT OFFICE.

EDWIN L. SMALLEY, OF EAST ORANGE, NEW JERSEY.

ELECTRIC FURNACE.

Application filed August 6, 1920. Serial No. 401,717.

To all whom it may concern:

Be it known that I, EDWIN L. SMALLEY, a citizen of the United States, and resident of East Orange, in the county of Essex and State of New Jersey, have invented certain new and useful Improvements in Electric Furnaces, of which the following is a specification.

This invention relates to electric furnaces, and my improvement is directed to certain novel means of supporting and engaging the heating elements thereof against the interior surfaces of such furnaces.

Particularly in the instance of a furnace having a housing composed of bricks of pressed infusorial earth, or of other suitable material which is a non-conductor of electricity, my invention comprehends the integral formation with said bricks, at their surface exposed to the furnace interior, of reception means for the resistance conductors constituting the heating units, and with said reception means I provide locking means to retain the heating units in such engagement and positively hold them compacted snugly against the interior surfaces of the furnace.

As an example of my invention I form upon the housing bricks, at their surfaces which are to be exposed to the furnace interior, a series of projections, or bosses, arranged in spaced relation, and in separated groups and tiers of groups, so that parallel strands of a resistor, may be lodged between adjacent projections or bosses, and pins of porcelain or other suitable material which is a non-conductor of electricity are then entered within aligned holes that extend through each series of said projections or bosses, beyond the lodged resistor strands, to prevent extrusion thereof.

Other features and advantages of my invention will hereinafter appear.

In the drawings:—

Figure 1 is a front sectional elevation of a furnace equipped with my improved resistor lodgement and securing means.

Fig. 2 is an enlarged, detail side view in section of the resistor lodgement and securing means,

Fig. 3 is a front view thereof, reduced, and

Fig. 4 is a detail of a modification.

In the example of an electrical furnace

illustrated in Fig. 1, it is seen to include the housing brick 1, whose surface is exposed to the furnace interior.

Usually the heating elements, as resistance conductors in the form of coils of return bend or other character, have been carried by unit refractories or plates with which the interior surface of the furnace is lined, but with the aid of my present improvement I am able to dispense with all such lining plates. Instead I provide the housing brick itself with projections or bosses 2, arranged in groups, and directed towards the furnace interior. The projections or bosses in each group are spaced apart sufficiently for the lodgement, between adjacent projections or bosses, of a resistor strand, and if the resistor is of the return bend type, having parallel strands 3, as here shown, then the interspaces separating the projections or bosses in a group will coincide with the spaced arrangement of the strands, and thus will receive said strands, which are thereby respectively supported and insulated one from another.

The groups of projections or bosses 2 are only arbitrarily indicated in the drawing as each including six projections or bosses for the containment of a return bend coil having that number of strands, but obviously said number may be varied. As represented in Fig. 2, a number of groups, 4, of said projections or bosses are provided, in lateral spaced arrangement, with their respective projections or bosses and interspaces aligned, so that a lateral series of said groups will unitedly support all the strands of a complete return bend coil throughout the full length thereof.

Thus the upper tier of groups 4 of Fig. 2 is shown as containing the heating element 3, having the bends 4, that extend around the respective projections or bosses at one end of the tier, while the terminals 5 project from the other end, for inclusion in an electrical circuit (not shown) according to usual furnace practice.

The projections or bosses in a group are provided with aligned orifices 6, which extend therethrough in parallelism with the housing surface, spaced therefrom sufficiently to clear the contained resistor strands, and a pin or the like 7 of porcelain or other suitable material that is a non-conductor of

electricity, is removably entered in said aligned orifices, to thus comprise a guard or lock to retain the resistor or heating element in its lodged position. Said pin 7 is shown 5 as having a head 8 to serve as a stop in co-action with the uppermost projection or boss, and to permit its withdrawal for the removal of the resistor.

When there is more than one tier of 10 groups 4 in a single plane, the groups of adjacent tiers are disposed in staggered relation, as per the example in Fig. 2, where two of such tiers are shown, because by this means the pins 7 in a lower tier are thereby 15 rendered capable of withdrawal through the spaces separating adjacent groups of an upper tier.

In Fig. 1 the surfaces of the side walls of 20 the furnace housing are shown as provided with exposed heating elements, lodged and locked in position in the manner described, and the same is also true of the upper and lower surfaces of the housing interior, excepting that the heating element in the bottom surface, with its lodging and retaining means, may, when desirable, be covered by a refractory plate, as indicated at 9 in said figure.

It should also be noted that in the cases 30 where more than one tier of groups are employed, in the staggered relation referred to, the adjacent projections or bosses of succeeding tiers provide between them the lodgement spaces for a final strand in a resistor element.

It will be appreciated that by the herein 40 described means of securing resistance conductors in exposed relation against the surface of the housing brick, early heating effect is provided, and also the contingency of broken unit refractories, thus needing replacement, is eliminated.

The projections or bosses provided upon 45 the surface of the housing brick may be formed integrally therewith, but may instead be in the form of separate members, having suitable means of engagement with the housing. Thus, in Fig. 4, I have shown supporting means 10 like those employed in 50 my Patent No. 1,346,854. Plates, as 11, are carried by supports 10, said plates having the projections or bosses 12, which receive between them the resistors 13, and pins 14 are entered through orifices provided therefor in said projections or bosses, to retain 55 the resistors in their lodged position.

Variations within the spirit and scope of my invention are equally comprehended

herein by virtue of the foregoing disclosure.

60

I claim:

1. An electric furnace having its housing exposed to the furnace interior, means engageable with the housing for the inwardly uncovered, removable lodgement of a resistance conductor, and movable securing means for said conductor.

2. In an electric furnace, in combination, a housing whose inner surface is exposed to the furnace interior, a return-bend heating 70 element having parallel strands, a group of spaced bosses upon said housing surface, whereof adjacent bosses permit the lodgement between them of said strands respectively, and removable means to secure said strands 75 in their lodgement.

3. In an electric furnace, in combination, a housing whose inner surface is exposed to the furnace interior, a return bend heating element having parallel strands, a group of 80 spaced bosses upon said housing surface, whereof adjacent bosses permit the lodgement between them of said strands, respectively, said bosses having aligned orifices, and a pin of non-conductive material removably entered in said orifices to retain said strands in their lodged position.

4. In an electric furnace, in combination, a housing whose inner surface is exposed to the furnace interior, a return bend resistance 90 conductor having parallel strands, laterally separated groups of spaced bosses upon said housing surface, adjacent bosses in each group being aligned to afford lodgement between them for a conductor strand 95 in exposed relation, and removable securing means for said strand.

5. In an electric furnace, in combination, a housing whose inner surface is exposed to the furnace interior, return bend resistance 100 conductors having parallel strands, tiers of laterally separated groups of spaced bosses upon said housing surface, whereof adjacent bosses in each group are aligned to afford lodgement between them for a conductor strand 105 in exposed relation, each group of bosses having aligned orifices, a removable lock pin for said strands in said orifices, and the groups of bosses in said tiers being staggered for the entry and removal of said pins.

Signed at New York, in the county of New York and State of New York, this second day of August, A. D. 1920.

EDWIN L. SMALLEY.
